UNITED STATES PATENT OFFICE.

JAMES C. LEDBETTER, OF BROOKLYN, NEW YORK, ASSIGNOR, BY MESNE ASSIGNMENTS, TO UNITED STATES HOFFMAN MACHINERY CORPORATION, OF NEW YORK, N. Y., A CORPORATION OF DELAWARE.

PRESS TOGGLE.

Application filed September 2, 1920. Serial No. 407,698.

To all whom it may concern:

Be it known that I, JAMES C. LEDBETTER, a citizen of the United States, residing at the borough of Brooklyn, city of New York, in the county of Kings and State of New York, have invented certain new and useful Improvements in a Press Toggle, of which the following is a specification.

This invention relates to press toggles, and more particularly to improvements in toggle leverages and similar mechanism employed to operate the pressing head of garment press or the platen of presses.

An object of this invention is to produce an improved type of toggle mechanism, or leverage for use in connection with presses of all kinds, or even machines of other classes, which develops great power at the expenditure of minimum energy applied by the operator to the toggle so as to obtain great pressure on the pressing head or platen of presses.

In the accompanying drawings, Fig. 1 illustrates one type of press which uses a toggle mechanism of the character forming the subject matter of this invention; and Fig. 2 shows a modified or elementary construction of the toggle removed from the press but shown in connection with the press lever and head.

A toggle leverage for presses constructed in accordance with the plans of this invention employs one simple toggle linkage which is connected to the parts of the machine to be worked under pressure, as for example the press lever of the garment press, and which is likewise connected to a prime mover such as a foot lever or other suitable device. A connection is established between the toggle and the prime mover for the purpose of straightening the toggle whereupon the toggle acts as a strut thru which force is transmitted to exert pressing operations. A feature of the invention resides in means for causing the pressing head or platen to close very rapidly with an expenditure of minimum power, followed by a slow motion pressing operation of great power developed thru the high leverage ratio obtained with a toggle mechanism of this character.

In presenting a more complete disclosure of the invention, there is shown a frame 4 on which is fulcrumed the press lever 5 on one end of which is mounted the usual type of pressing head 6 and on the other end of which is attached the toggle leverage device comprising this invention.

A simple toggle comprises links 8-9 pivoted together at 10. The upper end of the toggle is pivoted at 11 to the press lever 5, and in some instances the upper end of the toggle is attached to an adjustment screw device 12 ordinarily used to vary the pressing coaction between the head 6 and the object to be pressed or treated.

A foot lever 14 is fulcrumed at 15 in the frame 4, and this lever 14 has an upstanding arm 16 operating as an integral part thereof. The foot lever 14 and arm 16 are therefore made in the form of a bell crank, and as later seen performs the double function of straightening the toggle 8-9 and exerting thrust upwardly thru the toggle. A spring 13 has one end thereof attached to the frame 4 and the other end attached to the foot lever 14 so as to return the foot lever to an upwardly normal position when the machine is not in operation.

A short lever arm 17 is also fulcrumed on the pin 15 and capable of motion thereon relatively to the foot lever 14 and the lower part of the toggle is pivotally supported by this lever arm. The short lever arm 17 may be made with a projecting part 18, which is pivotally confined between the bifurcated part 23 of the foot lever 14 so that these two lever elements 14 and 17 form a continuous and one piece lever capable of either working together, or having slight relative motion one to the other about the pin 15 at certain stages of operation. The lever arm 17 is made with a shoulder 19 which rests against a stop 20 when it does not rest against the foot lever, thereby limiting the downward movement of the lever arm 17. A shoulder 21 is made on the foot lever 14 and disposed radially in respect to the fulcrumed point 15 so that this shoulder abuts the shoulder 19 on the lever arm 17. This construction and arrangement of the parts 14 and 17 makes

them work together as an integral and one piece lever during one stage of the operation, and during another stage of the operation the two parts 17 and 14 have relative motion 5 one on the other.

A link 24 is pivotally connected at 25 to one of the links of the toggle 8-9, and this link has a slot 25 made in the other end thereof, which slot is formed concentric with 10 the foot lever fulcrum point 15. One end of the slot 25 terminates in an offset shoulder 26, and a pin 27 is anchored to the arm 16 and confined in the slot 25 so as to normally rest against the shoulder 26. The front end 15 of the link 24 is made in the form of an inclined plane or cam 28, and a roller 29 is carried on the frame 4 and in contact with the cam 28 to support the link 24. The roller 29 therefore acts as a support and guide 20 for the front end of the link 24. A spring 30 has one end connected to some point of the link 24 and the other end thereof connected to the arm 16 which acts to keep the link 24 in downward contact with the roller 25 29 and to confine the pin 27 in its resting place against the shoulder 26.

In the operation of the toggle leverage above set forth and illustrated in Fig. 1, the operator applies pressure on the foot lever 30 piece 22 which oscillates the bell crank arm 16, moves the link 24 forward thus bringing the toggle 8-9 into approximately straightened position, with the cam 28 resting upon the roller 29; and likewise the shoulder 35 21 of the foot lever engages the shoulder 19 of the lever arm 17. In this manner the press lever 5 is swung about its fulcrumed point to bring the head 6 downwardly against the bed of the press. During the 40 motion of parts just described, it is to be noted that comparatively little effort was necessarily exerted on the foot lever 14, and furthermore the press lever 5 was swung at a comparatively rapid rate. During this 45 movement of the parts, the bell crank arm 16 and the link 24 are the active elements which straighten the toggle 8-9 and swing the press lever and head 6 into pressing position, yet these active elements do not necessarily exert any great degree of leverage 50 against the press lever 5.

The actual pressing operation immediately follows after the machine parts have reached that stage of movement above described and shown in Fig. 1. The operator continues downward pressure on the foot piece 22 which thrusts the link 24 slightly forward to complete the straightening action of the toggle 8-9 and which action 55 causes this toggle to move slightly past its center line; and simultaneously with this motion the cam 28 rides upon the roller 29 thus disengaging the shoulder 26 from the pin 27. This disengagement of parts permits the pin 27 to move freely in the slot 25,

and at the same time it is to be noted that the forked end of the link 24 now rests firmly against the roller 29 and therefore braces the toggle 8-9 against further sidewise or lateral movement. Inasmuch as the toggle 70 8-9 has reached a position slightly beyond a line drawn thru its pivotal centers and is restrained against further movement due to the bracing action of the link 24, the toggle 8-9 now functions as a strut thru which 75 high pressure may be transmitted to the press lever.

By the time this cycle of operation is reached, the shoulder 21 has contacted the shoulder 19, which in effect resolves the two 80 parts 14 and 17 into one and a single lever, with the short end 17 and the long end 14 of such comparative lever length ratio as to give the lever end 14 a very high leverage over the lever end 17. The operator is therefore able to exert great force thru the strut 85 toggle 8-9, and as he works up and down on the foot piece 22 to execute pressing movements of the head 6 down on the press bed, the pin 27 floats freely back and forth in the slot 25 which does not effect the stationary bracing position of the link 24.

After the operator has completed the pressing operation and removed his weight from the foot piece 22, the spring 13 acts to return all parts to normal inactive position, thus causing the toggle 8-9 to break rearwardly, and letting the lever arm 17 drop downwardly against the stop 20.

One of the advantages in constructing the foot lever 14-17 in two parts is that the bell crank 14-16 is permitted to complete its function, that of straightening the toggle 8-9, prior to the inception of the upward thrust thru the toggle; and this is an advantage because the toggle cannot transmit thrust until it has reached its straightened position.

Referring now to Figure 2 in the drawings, it is noted that the construction of the mechanism is similar to that hereinbefore described, but that the foot lever 32 is made integral with the lever arm 33. The foot lever likewise has the upstanding arm 34 and a connecting link 35 pivotally joining the bell crank 32-34 with the toggle 8-9.

The operation of this leverage mechanism is quite similar to the operation of the mechanism previously described, but with the exception that the lever arm 33 is thrusting 110 upwardly on the toggle 8-9 simultaneously with the straightening action of the bell crank 32-34 exerted against the toggle.

Furthermore the bell crank arm 34 does not have a disengageable connection with the link 35 which causes the toggle 8-9 to oscillate slightly during final pressing action. But it is pointed out that a disengageable connection may be provided between the parts 34 and 35 which would produce an 125

effective and well balanced operating mechanism comparing favorably to the leverage mechanism as described.

Having thus described the construction and operation of the invention, the following claims are made therefor:--

1. A toggle and leverage mechanism for presses of the type having a press head or platen raised or lowered by a press lever or 10 equivalent means, comprising a foot lever fulcrumed in the press frame, an upstanding arm made a part of the lever, a toggle pivotally connected with the aforesaid press lever, and connecting means established between the toggle and upstanding arm whereby the toggle is straightened by working the foot lever through a portion of its path of movement, and additional connecting means established between the foot lever and the 15 toggle whereby a further and final movement of the foot lever produces an upward thrust through the toggle.
2. In a press, the combination of a press-head; a lever supporting the same; a toggle, 20 one end of which is connected to the supporting lever for swinging said lever; a foot lever; a lost motion connection between the foot lever and the toggle for straightening the latter; and a second lost motion connection 25 between the foot lever and the toggle for applying thrust to the toggle after the same has been straightened.
3. An operating mechanism for presses 30 of the type having co-operating pressing members movable one in relation to the other, a toggle connected with one of the pressing members and adapted to open the press when broken and close the press when straightened, a bell-crank for straightening 35 the toggle and closing the press under moderate pressure, and a lever arm carried by the bell crank to move the straightened toggle to impose high pressure on the press.
4. An operating mechanism for presses 40 of the type having co-operating pressing members movable one in relation to the other, a toggle arranged to move one of the pressing members, a foot lever, an upstanding arm carried by the foot lever and connecting 45 with the toggle for producing a straightening action on the toggle, a lever arm co-operating with the foot lever and being connected with the aforesaid toggle and being movable in relation to the foot lever in 50 such a manner that it is inactive during the straightening movement of the toggle but subsequently moves with the foot lever to impart a short movement of great force through the straightened toggle.
5. The combination of a press head; an actuating lever; a movable support constructed and arranged to be engaged and moved by said actuating lever in the final portion of the actuating movement thereof; 55 a toggle linkage connecting said press head and support, and capable when straightened, of transmitting motion of said support to said head; a releasable connection between the toggle linkage and the actuating lever for straightening the toggle by the initial 60 actuating movement of the actuating lever; and means for releasing said connection as said actuating lever approaches its limit of actuating movement.
6. A toggle and leverage mechanism for 65 presses having a press lever, a press head, or a platen to be worked, comprising a foot lever made in two parts each of which is pivoted relatively to the other, a connection established between one lever part and the toggle for straightening the toggle, and a connection made between the other lever part and toggle for subsequently transmitting thrust thru the toggle.
7. A toggle and leverage mechanism for 70 presses having a press lever, a press head or a platen carried by the press lever, comprising a toggle connected with the press lever and capable of first being straightened to 75 form a strut to transmit force, a bell-crank, a connection between the bell-crank and the toggle whereby the toggle is moved into said straightened position, and means for releasing the connection after the toggle is straightened, a lever arm supporting the 80 toggle, a foot lever associated with the lever arm, and means to resolve the lever arm and foot lever into a one-piece lever for exerting a thrust thru the straightened strut-like toggle subsequent to the aforesaid releasing action.
8. An operating mechanism for presses 85 of the type having co-operating pressing members movable one in relation to the other, a toggle for opening and closing the pressing members, a bell crank having a treadle piece, a link establishing a connection between the bell-crank and the toggle for producing a straightening action on the toggle, a lost-motion connection employed by the 90 link to permit the bell-crank to continue in motion after the toggle is straightened, and a lever arm made a part of the bell-crank to impart a slow movement of great force 95 through the straightened toggle during continued motion of the bell-crank.
9. An operating mechanism for presses 100 of the type employing co-operating pressing members movable one in relation to the other, a toggle to open and close the press, a foot lever, a connection made between the foot lever and toggle to produce a straightening action on the toggle, means to render 105 inoperative the connection between the toggle and foot lever after the toggle is straightened so the foot lever may continue its movement, a relatively short lever arm having connection with the foot lever and having connection with the toggle, said lever arm having a lost-motion connection with the 110
- 120
- 125
- 130

- foot lever in order that it stands inactive during the movement of the foot lever to straighten the toggle, and means to eliminate the lost-motion connection simultaneously with the straightening of the toggle to cause the lever arm to move with the foot lever to impart a slow movement of great force through the straightened toggle as the foot lever continues its movement.
- 10 10. An operating mechanism for presses of the type employing relatively movable pressing members movable one in relation to the other, a toggle to operate the pressing members, a foot lever to straighten the toggle, a lever arm carried by the foot lever and having a lost-motion connection with the foot lever and having connection with the toggle, shoulders formed on the foot lever and lever arm to take out the lost-motion connection so that the lever arm and foot lever work in joined relation to impart a movement of great force through the straightened toggle.
- 15 11. An operating mechanism for presses of the type having co-operating pressing members movable one in relation to the other, a toggle to close the press through a straightening movement thereof, a foot lever, a connection between the foot lever and toggle for straightening the toggle, a
- lever arm connected with the foot lever and having a supporting connection with the toggle, means for rendering inoperative the connection between the foot lever and toggle when the toggle reaches a straightened position, means for rendering inoperative the connection between the lever arm and foot lever during the straightening period of the toggle, and means for rendering operative the said connection between the lever arm and foot lever after the toggle is straightened to produce movement through the toggle.
- 20 12. The combination of a press head; a movable actuator; a toggle connected with said press head; a toggle straightening means and a toggle stressing means each connected with said toggle; and lost motion connections between said actuator and said straightening means and between said actuator and said stressing means, constructed and arranged to terminate the straightening action and initiate the stressing action at points intermediate the limits of motion of the actuator.
- 25 In witness whereof I hereunto affix my name in the city of New York, this 22nd day of July, 1920.
